UNITED STATES PATENT OFFICE.

CHARLES F. STODDARD, OF BOSTON, MASSACHUSETTS, ASSIGNOR TO AMERICAN PNEUMATIC SERVICE COMPANY, OF DOVER, DELAWARE, A CORPORATION OF DELAWARE.

PNEUMATIC-DESPATCH-TUBE SYSTEM.

No. 923,308.

Specification of Letters Patent.

Patented June 1, 1909.

Application filed June 20, 1907. Serial No. 379,836.

To all whom it may concern:

Be it known that I, CHARLES F. STODDARD, of Dorchester, Boston, in the county of Suffolk and State of Massachusetts, have invented certain new and useful Improvements in Pneumatic - Despatch - Tube Systems, of which the following is a specification.

My invention relates to new and useful improvements in terminals for pneumatic despatch tube apparatus and especially to such apparatus wherein large carriers are used for the transmission of mail matter, merchandise and the like.

The object of my invention is to produce a machine simple in construction and efficient in operation and one which will automatically handle a second carrier while the first is being discharged on to the receiving table.

In the accompanying drawings which illustrate a construction embodying my invention, Figure 1 is a longitudinal section through the terminal with parts in position to receive a carrier; Fig. 2 is a similar view showing the position of the parts just after a carrier has entered the terminal; Fig. 3 is a similar view showing position of parts with both gates down and the carrier between the gates; Fig. 4 is a similar view showing all parts in the opposite direction from that shown in Fig. 1, the machine just discharging a carrier.

Like letters of reference refer to like parts throughout the several views.

The main transmission tube A is located in alinement with the compression chamber A² of the terminal and beyond the slotted casing A' through which the pressure passes into the return tube A³. Located on the upper side of the compression chamber A² is the cylinder D⁴ connected with the compression chamber A² by the pipes C⁵ and C⁶ and located within said cylinder is the piston D², connected by the rod D³ with the piston D' which in turn is connected by the rod D⁵ to the rod D⁷ by the hinged joint D⁶. The rod D⁷ is pivotally connected to the finger D⁸ at E, and this finger D⁸ swings on the bracket E² to which it is pivotally connected at E', and this finger D⁸ normally extends into the path of the discharging carrier as shown in Fig. 2. The air supplied for operating the inner and outer gates B and B² in the terminal enters through the pipe C into the valve-casing D and is conveyed into the top of the inner and outer cyl-

inders B⁶ and B⁵ by the pipes C' C² and operates the pistons B⁴ B⁷, to which are respectively connected the gates B and B² by the piston rods B³ and B⁷.

The carrier coming into the compression chamber A² is brought to a stop by the compression of the air in front of it as the gate B² is closed. This pressure passes by the pipe C⁶ into the cylinder D⁴ and forces the piston D² to the right of the cylinder D⁴, as shown in Fig. 2. This movement of the piston D² moves the piston-valve D' from the position shown in Fig. 1 to that shown in Fig. 2 and also brings the finger down into the position shown in full lines Fig. 2. The air-supply entering the valve-casing D through the pipe C, then passes through the pipe C' to the upper side of the piston B⁴ in the cylinder B⁶, and closes the gate B. As the piston B⁴ reaches the lower end of the cylinder B⁶ it passes the port P, which admits the pressure to the under side of the piston B⁷ in the cylinder B⁵ through the pipe C⁴. This pressure raises the piston B⁷ to the upper end of the cylinder B⁵, causing the raising of the gate B², which is connected to the piston B⁷ by rod B'. A portion of the pressure from the line A passes through the port P² in the gate B into the chamber A² back of the carrier and forces the carrier out of the chamber A² on to the table A⁴. In this position of the parts, Fig. 2, the finger B⁸ is in the path of the carrier, which strikes it as it comes on to the table A⁴ after it has passed the outer gate B². The finger D⁸ is moved from the position shown in full lines Fig. 2 to that shown in full lines Fig. 1 by the carrier, which moves the piston-valve from the position shown in Fig. 2 to that shown in Fig. 1, thereby opening the pipe C' to the atmosphere to allow the pressure in it and the cylinder B⁶ to exhaust to the atmosphere. The pressure from the pipe C then passes through the pipe C² into the cylinder B⁵ above the piston B⁷ and forces it down into the position shown in Fig. 1. As the piston B⁷ reaches the lower end of the cylinder B⁵ it passes the port P' and allows the pressure on the upper side of the piston B⁷ to pass through the pipe C³ to the under side of the piston B⁴ in the cylinder B⁶ thereby raising the piston B⁴ to the position shown in Fig. 1, which places the apparatus in position to receive another

carrier. The pipe C^5 connected to the cylinder D^4 is for the purpose of balancing the piston D^2 when the machine is not in operation.

A^9 is a suitable buffer to stop the carrier 5 when it reaches the end of the table A^4 .

In the automatic mechanism for controlling the second carrier, R is a slotted casing similar to the slooted casing A' which is placed in the transmission tube A far enough 10 back from the slotted casing A' to give the receiving chamber R' sufficient time to cushion the carrier as will be hereinafter explained. The slotted casing R is connected to the return tube A^3 by the tube R^2 . Located in the tubes A^3 and R^2 are the butterfly valves R^3 and R^4 , connected by the cranks R^5 and R^6 to the connecting rods R^7 and R^8 , which are in turn connected to the piston rod R^9 . This piston rod R^9 is securely fastened to the piston T which moves 20 in the cylinder T' . This cylinder T' is conveniently fastened to the receiving chamber R' by the bracket T^2 . One end of the cylinder T' is connected by the pipe C^8 with the port P^4 of the cylinder B^6 . This port P^4 is placed just below the piston B^4 when it is in its uppermost position. The opposite end of the cylinder T' is connected by the pipe C^9 with the top end of the cylinder B^6 . The 25 butterfly valves R^3 and R^4 are so connected together through the piston T that one will be wide open and the other completely closed when the piston T is at one extreme end of the cylinder T' and vice versa. The compression spring S tends to hold the piston T in the position shown in Fig. 2.

When the machine is in its normal position ready to receive a carrier, the under side of the piston B^4 is under pressure and the upper 40 side under exhaust; therefore, the pipe C^8 contains air under pressure and the pipe C^9 does not contain air under pressure, and so the respective ends of the cylinder T' are under pressure and this pressure holds the piston T against the spring S in the position 45 shown in Fig. 1. When the machine is in this position, the butterfly valve R^3 is open and the valve R^4 is closed, therefore, the current of air passes from the transmission tube 50 A straight through the slotted casing R and the receiving chamber R' through the slotted casing A' and into the return pipe A^3 .

A carrier, upon entering the receiving chamber A^2 , raises the pressure in front of it 55 by cushioning and thereby moves the piston valve D' into the position shown in Fig. 2, changing the air under exhaust on the upper side of the piston B^4 to pressure, and the air under pressure on the under side of the piston B^4 to exhaust, and likewise the air in the pipes C^9 and C^8 is changed so that the piston T is moved to the position shown in Fig. 2, butterfly valve R^3 closed, and butterfly valve R^4 open, so that the current of air now passes

from the transmission tube A through the slotted casing R into the return pipe A^3 through the pipe R^2 . As the piston B^4 is moved down to the position shown in Fig. 3, it passes the port P^4 and the air pressure above the piston B^4 passes through the port P^4 into the pipe C^8 , thereby balancing the piston T , but the piston T held in its position by spring S . After the gate B is closed, the gate B^2 opens, and the carrier is discharged on to the table A^4 engaging the finger D^8 and throwing the piston D' into the position shown in Fig. 1, thereby connecting the pipe C^2 with pressure and the pipe C' with exhaust, which connects the upper end of the cylinder B^6 with exhaust and also the pipes C^8 and C^9 . Connecting the pipes C^8 and C^9 with exhaust leaves the piston T still in balance, and the spring S continues to hold it in the position shown in Fig. 4. The machine then starts to return to its normal position, the gate B^2 closing before the gate B opens, but the port P^4 remaining connected with exhaust until the piston B^4 reaches the upper end of the cylinder B^6 , completing the cycle of operation. When the port P^4 comes 90 under pressure which is transmitted to one end of the cylinder T' through the pipe C^8 , this forces the piston T to the end of the cylinder as shown in Fig. 1, thereby opening the pipe A^3 and closing the pipe R^2 .

It will be seen that as soon as a carrier enters the machine and the positions of the butterfly valves R^3 and R^4 are changed from that shown in Fig. 1 to that shown in Fig. 2, the function of the receiving chamber R' 100 changes from acting as a continuation of the transmission tube A to acting as a cushioning chamber so that should a carrier come into the machine before it has completed its cycle of operation, it will be brought to a standstill in the receiving chamber R' by cushioning on the air in front of it and the current of air passing from the transmission tube through the slotted casing R into the pipe R^2 will not be interrupted and the carrier 110 will not strike against the gate B . At the instant the piston B^4 reaches the extreme upper end of the cylinder B^6 as the machine completes its cycle of operation, the positions of the butterfly valves R^3 and R^4 are quickly 115 reversed, and should a carrier be in the receiving chamber R' , the current of air, not having an avenue of escape back of the carrier will start it in motion and it will enter the receiving chamber A^2 in the same manner 120 as a carrier does under normal conditions, and in raising the pressure of the air in front of it by cushioning, would start the operation of the machine and discharge it on to the table A^4 in the usual way.

Having thus described the nature of my invention and set forth a construction embodying the same, what I claim as new and

desire to secure by Letters Patent of the United States is:

1. In apparatus of the class described, a transmission tube, a return tube, a receiving chamber in said transmission tube having communications at its opposite ends with said return tube, a gate for opening and closing the outer end of said chamber, valves controlling said communications, and means operating when the gate is closed to turn said valves to close the communication at the outer end of said chamber and to open the communication at the inner end of said chamber and also operating to reverse the valves when the gate is open.

2. In apparatus of the class described, a transmission tube, a return tube, a receiving chamber in said transmission tube having communications at its opposite ends with said return tube, a gate controlling the outer end of said chamber, valves controlling said communications, means normally holding said valves to close the communication at the outer end of said chamber and to open the communication at the inner end of said chamber, and pneumatically actuated mechanism operating to reverse said valves when the gate is open.

3. In apparatus of the class described, a transmission tube, a return tube, a receiving chamber in said transmission tube having communications at its opposite ends with said return tube, a gate controlling the outer end of said chamber, valves oppositely disposed in said communications, a rod connecting said valves, a spring normally pressing said rod to close the valve in the outer communication and to open the valve in the inner communication, and pneumatically actuated mechanism operating to move said rod against the action of said spring to reverse the valves when said gate is open.

4. In apparatus of the class described, a transmission tube, a return tube, a receiving chamber in said transmission tube having communications at its opposite ends with said return tube, a gate controlling the outer end of said chamber, a source of air-pressure,

a cylinder communicating with said source of air-pressure, valve-mechanism controlling the communications between said cylinder and said source of air-pressure, a piston in said cylinder to open and close said gate, valves in said communications between the receiving chamber and the return tube, and mechanism actuated by air-pressure from said cylinder operating to close the valve in the outer communication of the receiving chamber and to open the valve in the inner communication when the gate is closed and also operating to reverse the valves when the gate is open.

5. In apparatus of the class described, a transmission tube, a return tube, a receiving chamber in said transmission tube having communications at its opposite ends with said return tube, a gate controlling the outer end of said chamber, a source of air-pressure, a cylinder communicating with said source of air-pressure, valve-mechanism controlling the communications between said cylinder and said source of air-pressure, a piston in said cylinder to open and close said gate, oppositely disposed valves in said communications between the receiving chamber and the return tube, a rod connecting said valves, a spring normally pressing said rod to close the valve in the outer communication of said chamber and to open the valve in the inner communication, a secondary cylinder communicating with the cylinder of the gate-operating mechanism, a piston in said secondary cylinder connected with said rod actuated by the air-pressure from the gate-operating cylinder to move said rod against the action of said spring to reverse said valves when the gate is closed.

In testimony whereof, I have signed my name to this specification in the presence of two subscribing witnesses, this sixth day of June A. D. 1907.

CHARLES F. STODDARD.
